UNITED STATES PATENT OFFICE.

LEWIS H. KIRBY, OF KALAMAZOO, MICHIGAN.

AIR-INLET DEVICE FOR THE MANIFOLD OF AN ENGINE.

1,093,701.

Specification of Letters Patent.

Patented Apr. 21, 1914.

Application filed August 7, 1913. Serial No. 783,457.

To all whom it may concern:

Be it known that I, LEWIS H. KIRBY, a citizen of the United States of America, residing at Kalamazoo, in the county of Kalamazoo and State of Michigan, have invented certain new and useful Improvements in an Air-Inlet Device for the Manifold of an Engine, of which the following is a specification, reference being had therein to the accompanying drawings.

It is well known that when carburetors are set to give to internal combustion engines to which they are attached, their highest efficiency at low speeds, the mixture will be too rich to give the best results at high speeds and gasoline will be wasted.

The object of this invention is to provide a simple and efficient device which may be readily attached to the intake manifold of an engine to provide an auxiliary supply of air therefor at high engine speeds and is so constructed that it may be closed at will by the operator, and when open, will automatically operate to admit quantities of air in proportion to the speed of the engine.

A further object is to provide certain other new and useful features in the construction and arrangement of parts, all as hereinafter more fully described and more particularly pointed out in the appended claims, reference being had to the accompanying drawings, in which—

Figure 1 is a side elevation of an engine showing a device embodying the invention applied to the intake manifold thereof; Fig. 2, is an enlarged section of the device embodying the invention, showing the same as applied to an intake manifold of an engine; and Fig. 3 is an elevation of the same with parts broken away to show the construction.

In the drawings, A represents the intake manifold of an engine and B the carburetor which is attached to the lower end of the manifold.

The device embodying the invention comprises a tubular nozzle 1 which is externally screwthreaded throughout a portion of its length to engage a suitable screwthreaded opening in the side of the manifold A. The nozzle is provided with an enlarged head 2 at its outer end which is also externally screwthreaded and is internally formed to provide a suitable chamber therein for a disk valve 3 having a hollow stem 4 slidably within an externally screwthreaded tubular extension formed integral with an internally

screwthreaded cap 6 to engage the head 2 and close the chamber in said head. The cap is provided with a series of openings 7 closed by the valve 3 when said valve is seated against the inner side of the cap, and a coiled spring 8 within the tubular nozzle 1 is seated upon the closed end of said nozzle at one end and at its opposite end engages the valve to normally hold the same to its seat. The nozzle 1 is formed with a series of openings 9 through which the air entering the chamber in the head 2 through the openings 7, escapes from the nozzle into the manifold.

A disk closure 10 is rotatively mounted upon the tubular extension 5 of the cap 6 and is held seated against the outer surface of the cap over the openings 7 therein, by means of a coiled spring 11 sleeved upon the extension between said closure and a suitable nut 12 thereon. An internally screwthreaded cap 13 is engaged with the end of the extension to close said end and may be turned into engagement with the nut which forms a frictional lock therefor. A series of tubes 14 are provided in the disk 10 to register with the openings 7 in the cap 6 when the disk is turned by means of a suitable rod 15 attached to a laterally extending arm 16 on the disk. The rotation of said disk is limited by a lug 17 thereon adapted to engage a suitable stop 18 on the cap 6.

In operation, after the engine has attained a certain speed, the operator will turn the disk closure 10 by means of the rod 15 to open the holes 7 in the cap 6 and permit air to enter the chamber of the head 2, the partial vacuum created in said chamber by the operation of the engine pistons, causing the valve 3 to lift from its seat. The greater the speed of the engine, the greater will be the suction and the farther said valve will be lifted from its seat, thus regulating the inflow of air according to the speed. In passing through the perforations 9 of the nozzle, the air is divided into small streams which issue from the nozzle in all directions and thoroughly mix with the ingoing charges passing the nozzles on their way to the engine.

For the purpose of priming the engine in starting or for introducing a decarbonizing fluid into the engine cylinder, the cap 13 may be removed and a suitable tubular member (not shown) screwed in its place to conduct the fluid into the tubular member 5 from which it will flow through the hollow

stem 4 of the valve into the chamber of the head 2 and be drawn therefrom through the nozzle by the action of the engine.

Obviously changes may be made in the construction and arrangement of parts without departing from the spirit of my invention and I do not therefore limit myself to the particular form or arrangement shown.

Having thus fully described my invention

10 what I claim is:

1. In an air inlet device, the combination with the manifold of an engine, of a hollow head in communication therewith, an apertured cap carried by said head, a tubular extension carried by said cap, a spring pressed valve normally seated against the inner side of said cap and provided with a tubular stem slidably in the tubular extension of said cap, a manually controlled apertured closure member supported against the outer side of said cap and upon said tubular extension, and means carried by said tubular extension for holding said member against said cap.
2. A device of the type described comprising a hollow head, an apertured cap screwed thereon and provided with a tubular extension, a spring pressed disk valve normally seated against the inner side of said cap and adapted to be unseated by suction in said

head, a tubular stem carried by said disk 30 valve and movably supported in the tubular extension of said cap, a manually controlled apertured member carried by the extension of said cap, a nut mounted upon the outer end of said extension, and means interposed 35 between said nut and said closure member for holding said member normally against said cap.

3. In an air inlet device, the combination with the manifold of an engine, of a hollow 40 head in communication therewith, an apertured cap detachably mounted upon said head, a tubular extension carried thereby, a yieldable valve seated against the inner side of said cap, a stem carried by said valve and movable in said tubular extension, a manually controlled apertured closure member carried by said tubular extension, means upon said tubular extension for holding said closure member normally seated against the 45 outer side of said cap, and means adapted to limit the movement of said closure member.

In testimony whereof I affix my signature in presence of two witnesses.

LEWIS H. KIRBY.
